UNITED STATES PATENT OFFICE.

HENRY DIXON AND ADOLPH THIELE, OF DAYTON, OHIO.

SANITARY MILK-BOX.

1,261,220.

Specification of Letters Patent.

Patented Apr. 2, 1918.

Application filed March 28, 1917. Serial No. 157,990.

To all whom it may concern:

Be it known that we, HENRY DIXON and ADOLPH THIELE, citizens of the United States, residing at Dayton, in the county of 5 Montgomery and State of Ohio, have invented a new and useful Sanitary Milk-Box, of which the following is a specification.

This invention relates to sanitary milk boxes.

10 An object of the invention is to provide a construction in which bottles of milk and similar articles may be placed whereby they will be locked against thieves and unauthorized persons, and in which they will be kept sanitary by being protected from 15 cats, dogs and flies.

Another object of the invention is to provide a box of the above mentioned nature which may be automatically locked by the 20 milk man or other person delivering the goods, and which will be retained locked against unauthorized interference until actuated by a proper key.

The sanitary milk box can be fastened 25 to the wall or porch in any suitable manner.

In the accompanying drawings there has been illustrated one embodiment of the invention, in which:

30 Figure 1 is a front elevation of the same with the cover in closed position.

Fig. 2 is a front elevation upon a larger scale with the cover in raised position.

Fig. 3 is a horizontal sectional view upon 35 a larger scale on the line 3—3 of Fig. 1, looking in the direction of the arrow.

Fig. 4 is a vertical sectional view upon a larger scale on the line 4—4 of Fig. 1, looking in the direction of the arrow.

40 Fig. 5 is a detail plan view of the lock mechanism with a portion of the casing removed.

In the embodiment of the invention here shown there has been provided a box 1 having a bottom and a top 2, sides 3, and a back 4 connecting the sides, the top and bottom forming a structure open at the front, as indicated at 5. The box may be made of any suitable material such as sheet metal or the 45 like. In metallic structures, the top of the box is reinforced by means of a wooden slab or block 6 provided with clearance spaces 7. The front of the top is bent downwardly, forming a reinforcement 8 along the front edge of the block 6. The back 4 also is reinforced by a block or slab 9 which abuts

at its upper edge the bottom of the block 6. The block 9 is secured to the back in any suitable manner as by rivets or the like, and the box itself is adapted to be fastened to 60 the porch or other part of the house by suitable fastening devices 10 which extend through the reinforcing block 9 and through the back.

Within the box and attached to the block 65 9 adjacent to the top of the box are clamping holders 11. These holders may be of any suitable construction and are adapted to engage the bottles around the neck to retain the same in vertical position within the 70 box and spaced from the bottom substantially as shown. The holder herein shown, however, is of the construction shown and described in an application filed by one of us, Adolph Thiele, December 21, 1916, Serial No. 138,224.

The sides 3 are provided at their front edges with inwardly directed flanges 12 extending at right angles thereto. The flanges 12 are doubled providing a very strong 80 reinforcing construction, substantially as shown in Fig. 3.

A cover 13 is adapted to close the upper portion of the front of the box and is provided along one horizontal edge with a 85 marginal flange 14 arranged at right angles thereto and by the edge of which the cover is pivoted to the top of the box at 15 inwardly of the front edge thereof. The cover 13 is also provided with side flanges 16 arranged at right angles thereto and adapted when the box is closed to engage the outside thereof. The opposite horizontal edge of the cover 13 is also provided with a flange 17 spaced at its ends from the flanges 16 90 providing slots 18 into which the flanges 12 extend or project when the cover is in closed position. The construction above described is one which provides a very tight closure between the upper portion of the 100 front of the box and the cover, the flanges fitting closely against the box at the top and the sides, while the flange 17 extends inwardly between the inwardly extending flanges 12.

105 The cover is retained in locked position through the instrumentality of a lock comprising a casing 19 mounted upon the inside thereof. This lock has a pair of bolts 20 and 21 extending along the cover and 110 adapted to engage at their outer ends the inner sides of the flanges 12 and retain the

cover locked. The bolt 20 projects into the casing 19 at one side thereof through an opening 22, is guided therein and is provided within the casing 19 with a portion 23 extending at right angles to the projecting portion of the bolt 20 to the opposite side of the lock. The opposite end of the bolt is directed outwardly as indicated at 24 through a guiding opening 25, which is 5 diagonally opposed to the opening 22. The 10 portion of the bolt 20 within the lock casing is substantially Z shaped. The projecting portions of the bolts 20 and 21 are in substantial alinement, as clearly shown in Fig. 15 5. The intermediate portion of the bolt 21, however is provided with a portion 26 directed at right angles to the outer portions thereof toward the portion 24. A portion 27 of the bolt 21 extends parallel with the 20 portion 24 of the bolt 20 through the opening 25 and extends across the casing to a point beyond the transversely extending portion 23. The bolt 21 is here provided with a transversely extending portion 28 extending 25 parallel with the portion 23, and which terminates at the opposite side of the casing in a portion 29 directed at right angles thereto and extending outwardly through the opening 22 and parallel with the bolt 20, whereby the bolt 21 is retained in position and suitably guided. The intermediate portion of the bolt 21 is, therefore, substantially U-shaped.

Pivottally mounted within the casing of 35 the lock between the transversely extending portions 23 and 28 is an actuating plate 30 provided with lugs 31 and 32 arranged between the transversely extending portions of the bolts and adapted to rotate to cause 40 a separation of these parallel transverse portions. Intermediate the lugs 31 and 32 is a lug 33 adapted to be engaged by a suitable key, as shown in dotted lines in Fig. 5, whereby the plate may be rotated to separate the parallel transverse portions of the bolts causing the outer ends thereof to move 45 toward each other. The parallel transverse portions of the bolts tend to move toward each other by reason of springs 34 which 50 normally keep the outer ends of the bolts projected, as shown in Figs. 2 and 3.

The portions of the bolts outside of the lock casing and upon the cover are protected by means of casings 35 to prevent unauthorized manipulation of the bolts to unlock the 55 cover.

The outer ends of the bolts terminate in hooks 36 having suitable cam edges 37. These cam edges are engageable with the 60 inner edges 38 of the flanges 12, whereby the bolts are retracted when the cover is swung down against the front to allow the cover to swing into position. The bolts, however, immediately spring outwardly and engage 65 the insides of the flanges 12 by reason of

the springs 34, substantially as shown in Fig. 3, providing a very strong lock which prevents access to the box to remove the milk bottles.

Mounted upon the insides of the flanges 70 12 and arranged in alinement with the casings 35, are housings 39 into which the ends of the hooks 36 project when the cover is closed whereby the bolts and hooks are fully 75 protected against manipulation by unauthorized persons, the same being entirely inclosed throughout their lengths.

Upon the cover may be also arranged 80 clips 40 adapted to receive tickets and note paper of different kinds.

The box may also be provided with a suitable handle 41 at the top thereof, if so desired.

In use the box should be kept open and in the position shown in Fig. 2, until the milk 85 bottles are fastened in the holders 11 by the milkman. It should be noticed that the recesses or spaces 7 are immediately above the holders and allow the easy insertion and removal of the milk bottles and free play of 90 the tops thereof, as the bottles are swung outwardly and inwardly. After inserting the bottles in the holders the milkman can push down the cover when it will be automatically locked. The arrangement is such 95 that the milk bottles cannot be removed while the cover is down and locked. The cover serves as a lock or obstruction to prevent the swinging of the bottles sufficiently to allow them to spring out of the holders 100 11. On the other hand, the lower portions of the bottles will be fully exposed to the air and can be affected by atmospheric conditions and sunlight. It can also be easily seen whether the box contains milk or not. 105

While we have shown and described one embodiment of our invention, it is to be understood that we do not desire to be limited to the details of construction herein shown and described for obvious modifications will be apparent to anyone skilled in the art.

What is claimed is:—

1. The combination with a box reinforced at the top and the upper portion of the back, of holders adapted to engage the necks of milk bottles and fastened to the reinforced portion of the back, the reinforced top being provided with recesses whereby the bottles may be easily disengaged from the holders, a cover closing one side of said box, and means for locking said cover to the box.

2. The combination with a box open at the front and having sides provided at their front edges with inwardly directed flanges, of holders within the box adapted to engage the necks of milk bottles and retain them in vertical position, a cover, and a lock mounted on said cover and having bolts 130

adapted to engage said flanges upon the inside thereof whereby the cover is locked in position.

3. The combination with a box open at one side and having inwardly directed flanges, of holders for milk bottles mounted within the box, a cover provided with marginal flanges and pivoted by the outer edge of one horizontal flange to the top of said box inwardly of the front edge thereof, said cover flanges comprising side flanges adapted to engage the sides of the box and an opposite horizontal flange spaced from the side flanges whereby the inwardly directed flanges of the box may not interfere when the cover is in closed position, a lock mounted upon the inside of said cover and provided with bolts adapted to engage the inwardly directed flanges of the box to retain the cover in closed position.

4. The combination with a box having an open side, of clamping holders mounted interiorly of the box on the side opposite the opening and adapted to engage milk bottles, and a cover hinged to the box at its top and

movable downwardly over the open side to extend a considerable distance below the plane of the clamping holders and also adapted to swing upwardly above the plane of the top.

5. The combination with a box having an open side, of clamping holders mounted interiorly of the box on the side opposite the opening and adapted to engage milk bottles, a cover hinged to the box at its top and movable downwardly over the open side to extend a considerable distance below the plane of the clamping holders and also adapted to swing upwardly above the plane of the top, and means carried by the cover and engageable with the box to sustain said cover in its lowered position.

In testimony, that we claim the foregoing as our own, we have hereto affixed our signatures in the presence of two witnesses.
